UNITED STATES PATENT OFFICE.

ALBERT SCHREINER, OF DENVER, COLORADO, ASSIGNOR TO THE SCHREINER LADDER MANUFACTURING COMPANY, A CORPORATION OF COLORADO.

SUSPENSION-HOOK FOR EXTENSION-LADDERS.

1,244,645.

Specification of Letters Patent.

Patented Oct. 30, 1917.

Application filed March 29, 1916. Serial No. 87,494.

To all whom it may concern:

Be it known that I, ALBERT SCHREINER, a citizen of the United States, residing at Denver, in the county of Denver and State 5 of Colorado, have invented certain new and useful Improvements in Suspension-Hooks for Extension-Ladders, of which the following is a specification.

My invention relates to suspension hooks 10 of the type used in connection with sectional extension ladders, for the purpose of suspending one ladder-section from the rounds of another.

The principal object of my invention is 15 to provide a device of simple construction which consists of a keeper adapted for attachment to a side-bar of the ladder-section and a hook which is pivoted on said keeper and adapted to engage a round of a basal 20 ladder-section for the suspension of the relatively adjustable section to which its keeper is attached.

The hook has at its upper end an inclined 25 face which permits of its passing slidingly across the rounds of the basal ladder-section during upward motion of the section to which its keeper is attached, and the hook is furthermore provided with a pivoted latch which during downward movement of the 30 adjustable section of the ladder, is by engagement with the rounds of the lower section, moved to a position in which it bridges the round-engaging bend of the hook and thereby permits it to pass the rounds.

35 In the accompanying drawings in the various views of which like parts are similarly designated,

Figure 1 is a perspective view of my improved suspension hook in its operative relation to the side bar of a ladder,

Fig. 2, a longitudinal section of an extension-ladder showing the operative position of the hook on one with relation to a round on the other,

45 Fig. 3, a view similar to Fig. 2, showing the position of the hook while passing a round during downward movement of the ladder section to which it is attached, and

Fig. 4, a perspective view of the latch 50 which is pivoted on the hook.

In the drawings the reference numerals 2 and 3 designate the sections of an extension ladder which are each composed of a plurality of rounds 4 secured between two side-bars 5.

The rounds of the ladder are preferably made of metal bars of channel section.

My improved suspension hook comprises a keeper composed of a plate 6 provided with angularly disposed lugs 7 which engage an 60 edge of the side rail upon whose inner face the plate is disposed.

The plate has at its lower edge an outwardly projecting lug 8 which forms a recess 9 to receive the lower extremity of a hook 10 65 which is pivotally mounted on the keeper by means of a pin 12 extending through aligned openings in the lug 8 and the body-portion of the plate.

The plate has at its upper edge an integral 70 transversely-extending guide-rail 13 connected therewith at its ends by stops 14 and provided to guide the hook and limit its pivotal movement in opposite directions in the operation of the device.

The plate is furthermore provided with 75 apertures for the passage of screws 15 by means of which it is attached to the ladder-bar.

The hook-member of the invention 80 comprises a shank 16 which has at its lower end an aperture for its pivotal connection with the pin 12, and at its upper end a transverse, obliquely disposed bar 17 which is bent inwardly at one of its extremities to provide 85 the bill 18 which in practice is hooked over the round of the ladder-section from which the section to which the hook is attached, is suspended.

The upper face 19 of the transverse bar 90 of the hook slants from the bill upwardly to engage the rounds of the lower ladder-section during upward movement of the other section and thereby permit the hook to pass across said rounds.

Pivottally suspended from the shank of the hook at a point between its upper end and its portion engaging the guide-rail 13, is a latch 20 of curvilinear form which when the hook is in its normal, inwardly slanting 100 position in engagement with the forward stop of the guide rail, hangs with its lower end in a line with the rounds of the lower ladder-section.

The latch is composed of two arms 21 105 which are pivoted at opposite sides of the hook shank, and a cross-piece 22 which when the latch is in its suspended position engages the edge of the shank to limit the inward movement of the latch and which when by 110

engagement with a round of a ladder across which the hook is moved, the latch is moved upwardly, centrally engages the bill 18 of the hook to bridge the round-engaging bend 5 of the same.

In the operation of my invention, two of the herein described suspension devices are fastened oppositely upon the inner faces of the side bars of a ladder-section to engage 10 the rounds of a relatively stationary section against which the first-mentioned section is disposed.

When the upper section is moved upwardly to extend the ladder, the inclined 15 faces of the bars at the upper ends of the hooks, slide across the rounds of the lower section, each time moving the hooks about their pivots, it being understood that the hooks are normally maintained in a slanting position in engagement with the forward stop 14, by gravitation.

After the hooks have passed the round 20 from which the adjustable section is to be suspended, the section is lowered until the hooks engage said round as shown in Fig. 2.

When the section with which the hooks are associated is lowered to reduce the 25 length of the ladder, the latches are by engagement with rounds of the basal section, moved about their pivots into engagement 30 with the bills of the respective hooks as illustrated in Fig. 3, thereby bridging the round-engaging bends of the same and permitting the passage of the hooks across the rounds, 35 it being understood that during downward

movement of the adjustable ladder section, it may be suspended from any round of the basal section by moving the hooks upwardly past the round and then downwardly until they are in engagement therewith.

The upper portions of the hook shanks are reinforced as shown at 23 in the drawings to prevent breakage at the points of greatest stress.

Having thus described my invention what 45 I claim and desire to secure by Letters-Patent is:

In an extension ladder, a plate lying flat 50 against a side of a side-rail thereof, and having angularly disposed integral lugs 55 which bear against an edge of the same, said plate being rigidly secured to said side-rail and having at its upper end a transverse slot provided by a guide-bar which is integrally connected with the plate by means of stops, 60 and at its lower end, an integral outwardly projecting lug which forms a recess, a suspension-hook loosely extending through said slot and into said recess, a pivot pin occupying aligned apertures in the lug, the plate 65 and the hook, and a latch pivoted on the hook and having a cross-piece to engage the bill of the same, when moved upwardly about its pivot.

In testimony whereof I have affixed my 65 signature in presence of two witnesses.

ALBERT SCHREINER.
